DESIGN FOR A SINK CABINET

Charles S. Motter, Chicago, Ill.

Application October 19, 1944, Serial No. 115,862

Term of patent 7 years

(Cl. D4—2)

To all whom it may concern:

Be it known that I, Charles S. Motter, a citizen of the United States, residing in Chicago, in the county of Cook and State of Illinois, have invented a new, original, and ornamental Design for Sink Cabinet, of which the following is a specification, reference being had to the accompanying drawing, forming a part thereof,

In the drawing the single figure is a perspective view of the sink cabinet showing my new design, the end of the cabinet not shown being the same in appearance as the end shown in the drawing.

I claim:

The ornamental design for a sink cabinet, as shown and described.

CHARLES S. MOTTER.
